Gloovsky and Popeo, P.C.; Steve Jensen; Richard B. Emmons(57) **CLAIM**The ornamental design for a squeeze pouch, as shown and
described.**DESCRIPTION**FIG. 1 is a perspective view of the top, front and right side of
the first embodiment of the squeeze pouch;

FIG. 2 is a front view thereof;

FIG. 3 is a back view thereof;

FIG. 4 is a left view thereof, which is the same as the right
view thereof (i.e. a mirror image);

FIG. 5 is a top view thereof;

FIG. 6 is a bottom view thereof;

FIG. 7 is a perspective view of the top, front and right side of
the second embodiment of the squeeze pouch;

FIG. 8 is a front view thereof;

FIG. 9 is a back view thereof;

FIG. 10 is a left view thereof, which is the same as the right
view thereof (i.e. a mirror image);

FIG. 11 is a top view thereof; and,

FIG. 12 is a bottom view thereof.

The broken line showing of portions of the squeeze pouch is
included for the purpose of illustrating environmental struc-
ture and forms no part of the claimed design.**1 Claim, 6 Drawing Sheets**FIG. 2
